UNITED STATES PATENT OFFICE.

THOMAS J. DAVIS, OF SAN FRANCISCO, CALIFORNIA.

MILK-CAN CONTAINER AND SERVER.

1,169,933.

Specification of Letters Patent.

Patented Feb. 1, 1916.

Application filed February 13, 1915. Serial No. 7,965.

To all whom it may concern:

Be it known that I, THOMAS J. DAVIS, a citizen of the United States, residing in the city and county of San Francisco and State 5 of California, have invented new and useful Improvements in Milk-Can Containers and Servers, of which the following is a specification.

This invention relates to a milk can container and server, and particularly to improvements over a copending application entitled "Milk can container and server", filed January 11, 1915, Serial No. 1,555.

One of the objects of the present invention is to provide a cover for the container, which cover is provided with two perforating members, one to form a pouring opening and the other a vent opening in the can which the container supports.

20 Another object of the invention is to so mount the cover that it will serve as a lever to force the perforating members through the can after it has been placed within the container.

25 Further objects will hereinafter appear.

The invention consists of the parts and the construction and combination of parts as hereinafter more fully described and claimed, having reference to the accompanying drawings, in which—

30 Figure 1 is a central vertical section through the container, showing the can in position within the container. Fig. 2 is a plan view of the container. Fig. 3 is a section of the cover on line 3—3, Fig. 1.

More particularly described, A indicates a cylindrical shaped container in which a bottom is formed to support a milk can, such as indicated at 2, by spinning or otherwise 40 turning in an annular flange 3. Pivotedly mounted on the container, as at 4, is a cover 5, and formed integral with said cover is a pouring spot 6 which is provided at its lower end with an inwardly extending, perforating member 7. This perforating member 45 is of suitable size and shape, but preferably triangular in cross section, and is, furthermore, hollow to form communication between the interior of the can and the pouring 50 spout.

Surrounding the perforating member is a parking member 8 in the form of a rubber gasket or the like. This forms a parking 55 between the spout and the can to prevent leakage at this point. Formed integral or suitably secured in same, as at 9, is a second

hollow perforating member which forms a vent opening for the can. This is also provided with a gasket, such as indicated at 10, to prevent leakage between the cover and the can top. The container is otherwise provided with a handle 11 of suitable shape. The upper portion of this handle is slotted, as at 12, and a portion of the metal cut to form this slot is bent outwardly to form a 65 catch 13. A spring latch 14 formed integral with the cover or otherwise secured to same, as indicated at 15 is adapted to pass through the slot into locking engagement with the catch, when the cover is closed, thus forming 70 a simple, easily operated retaining means or lock to secure the cover in its closed position.

From the foregoing description it will be seen that the cover does not only serve the 75 function of a cover, but it also serves as a support and lever for the perforating members. The construction involved, furthermore, provides a simple, cheaply manufactured, sanitary device, as the perforating 80 members are so positioned that they are readily accessible for cleaning purposes. The construction involved, furthermore, permits a perforating member, such as indicated at 7, to be constructed of large diameter, as the leverage or pressure is large at 85 this point. Heavy condensed milks can, therefore, be poured from the container.

The materials and finish of the several parts of the device are such as the experience and judgment of the manufacturer may dictate.

I wish it understood that various changes in form, proportions and minor details of construction may be resorted to within the 95 scope of the appended claims, and that I do not wish to limit myself to the specific design and construction here shown.

Having thus described my invention, what I claim and desire to secure by Letters 100 Patent is—

1. In combination with a container, a cover therefor having a pouring spout which has its lower end depending from the cover and pivoted at its lower extremity to 105 the front side of the container, said container having an opening in its front side which registers with said spout, and a perforator connected to the spout and movable into and out of said opening so as to perforate the side of a can within the container 110 below its top.

2. In combination with a container, a cover therefor having a pouring spout disposed at the front side of the cover so that the spout is disposed over the front side of the container, means to pivotally connect the spout to the front side of the container below the container top so that the entire spout is mounted to swing toward and away from said front side of the container, and
- 5 a perforator carried by the spout and partaking of the swinging movements thereof so as to be movable into and out of a can within the container from a side of said can upon pivotal movement of the cover.
- 10 3. In combination with a container, a cover therefor having a pouring spout disposed at the front side of the cover so that the spout is disposed over the front side of the container, means to pivotally connect the spout to the front side of the container below the container top so that the entire
- 15
- 20

spout is mounted to swing toward and away from said front side of the container, a perforator carried by the spout and partaking of the swinging movements thereof so as to be movable into and out of a can within the container from a side of said can upon pivotal movement of the cover, a handle on the container having a slot, the metal displaced by the slot formation being left in connection with the handle and bent outwardly to form a catch, and a latch borne by the cover and adapted to enter the slot and engage with said catch.

In testimony whereof I have hereunto set my hand in the presence of two subscribing witnesses.

THOMAS J. DAVIS.
